(57) **CLAIM**

An ornamental design for a single-bladed cartridge for a straight razor, as shown and described.

DESCRIPTION

FIG. 1 illustrates a perspective view of a single-bladed cartridge for a straight razor.

FIG. 2 illustrates a side view of the single-bladed cartridge for a straight razor.

FIG. 3 illustrates an opposite side view of the single-bladed cartridge for a straight razor.

FIG. 4 illustrates a front view of the single-bladed cartridge for a straight razor.

FIG. 5 illustrates a back view of the single-bladed cartridge for a straight razor.

FIG. 6 illustrates a top view of the single-bladed cartridge for a straight razor.

FIG. 7 illustrates a bottom view of the single-bladed cartridge for a straight razor.

FIG. 8 illustrates a perspective view of the single-bladed cartridge for a straight razor; and,

FIG. 9 illustrates an environmental view of the single-bladed cartridge for a straight razor.

The broken lines shown in the drawings illustrate the environment and form no part of the claimed design.

1 Claim, 6 Drawing Sheets
